E. L. KOILE

DRAFTING SQUARE

Filed July 23, 1923

Inventor

Edgar L. Koile

UNITED STATES PATENT OFFICE.

EDGAR L. KOILE, OF STAUNTON, INDIANA.

DRAFTING SQUARE.

Application filed July 23, 1923. Serial No. 653,262.

To all whom it may concern:

Be it known that I, EDGAR L. KOILE, a citizen of the United States, residing at Staunton, in the county of Clay and State of Indiana, have invented certain new and useful Improvements in a Drafting Square, of which the following is a specification.

My invention relates to squares, and is particularly adapted to be used in making angular cuts, such as required on rafters, 10 stair cases, or the like.

An important object of my invention is to provide a square so constructed that one setting will serve to make numerous cuts of 15 the same angle.

Another object of the invention is to provide a square of the above mentioned character, which will make cuts to any angle of degree necessary.

20 A further object of the invention is to provide a square of the above mentioned character which can be adjusted to make cuts to the required rise per foot.

Other objects and advantages of the invention will be apparent during the course 25 of the following description.

In the accompanying drawing forming a part of this specification and in which like numerals are employed to designate like 30 parts throughout the same—

Figure 1 is a side elevation of apparatus embodying my invention.

Figure 2 is a plan view of same.

35 Figure 3 is a detail view of the cross-arm.

Figure 4 is a partial detail view of the square.

In the drawing, wherein for the purpose 40 of illustration is shown a preferred embodiment of my invention, the numeral 1 designates a square, preferably formed of steel, comprising a blade 2 and a tongue 3. The blade 2 is divided into any desired graduations as indicated at 4, while the tongue is 45 likewise divided into graduations as indicated at 5.

Connected to the square by means of a rivet 6, or the like, is a cross-arm 7, the ends of which are provided with extension 50 lugs 8. The upper edge of the cross-arm 7 is provided with graduations 9 which co-act with the graduations 4 and 5 on the blade 2 and tongue 3 respectively of the square 1. The lower edge of the cross-arm 7 is provided with a semi-circular extension 10, the

edge of which is divided into degrees as indicated at 11. The square 1 and the cross-arm 7 are provided respectively with the openings 12 and 13, for the purpose of allowing the rivet 6 to pass through and join same. The semi-circular extension 10 is provided with an opening 14, which permits a thumb screw 15 to pass through same. The square 1 is provided with a semi-circular opening 16 through which the thumb 65 screw 15 passes, and allows movement of the square 1 to the limits of the opening 16.

In the use of the device, the cross-arm 7 is placed along the edge of the member upon which work is to be performed, and held in 70 position by means of the lugs 8. The square is then placed at the required angle and the thumb screw tightened after which any number of boards or the like may be marked.

It is to be understood that the form of my invention herewith shown and described is to be taken as a preferred example of the same, and that various changes in the shape, size, and arrangement of parts may be resorted to without departing from the spirit 80 of my invention, or the scope of the subjoined claims.

Having thus described my invention, I claim:

1. A device of the character described, comprising a cross arm provided with an arcuate extension in the center thereof, and provided with graduations in the angular measure on the edge of the arcuate extension, a cross arm provided with graduations on its upper edge, an adjustable element comprising a square provided with graduations consisting of units of length formed on the lower edges of the said square, a plurality of lugs formed on the side of the cross arm, means for pivotally connecting the cross arm and square and means for rigidly securing the square to the cross arm.

2. A device of the character described comprising a cross arm provided with graduations on the upper edge thereof, an arcuate extension formed in the center of the cross arm bearing marks consisting of units of angular measure on the edge thereof, extension lugs formed on the extremities of the cross arm on the faces opposite the markings, an adjustable square comprising a blade and a tongue provided with graduations on the lower edge adapted to co-act with the

graduations formed on the cross bar, a pivot pin pivotally connecting the cross arm and square, an arcuate opening formed in the lower portion of the square adapted to receive a thumb screw secured to the cross arm for the purpose of locking the square with the cross arm.

In testimony whereof, I have affixed my signature in the presence of two witnesses.

EDGAR L. KOILE.

Witnesses:

IDA A. FERRELL,
FERN L. BEVIS.
